UNITED STATES PATENT OFFICE.

MAURICE M. FEINBERG, OF NEW YORK, N. Y.

DESIGN FOR A SIGN.

Application filed May 18, 1922. Serial No. 2,305. Term of patent 3½ years.

To all whom it may concern:

Be it known that I, MAURICE M. FEINBERG, a citizen of the United States of America, residing in New York city, State of New York, have invented a new, original, and ornamental Design for a Sign, of which the following is a specification, reference being had to the accompanying drawing, forming a part hereof.

In the drawing, the figure is a front elevation.

I claim:

The ornamental design for a sign, as shown.

MAURICE M. FEINBERG.
